John L. Noll INVENTOR

BY Victor J. Evans

ATTORNEY

UNITED STATES PATENT OFFICE.

JOHN L. NOLL, OF JUNIATA, PENNSYLVANIA.

MINIATURE LAMP.

Application filed April 7, 1924. Serial No. 704,828.

To all whom it may concern:

Be it known that I, JOHN L. NOLL, a citizen of the United States, residing at Juniata, in the county of Blair and State of Pennsylvania, have invented new and useful Improvements in Miniature Lamps, of which the following is a specification.

This invention relates to improvements in miniature lamps for decorative purposes, 10 toys and so forth and has for an object the provision of means which may be detachably associated with the sockets of ordinary Christmas tree electric lamps and with other miniature sockets to provide miniature lamp posts of an attractive and pleasing appearance.

Another object of the invention is the provision of a post of the above character which may be made of soft, easily worked 20 material to reduce cost of manufacture, reinforcing means being provided to stiffen the post and to provide a conduit for a conductor wire.

Another object of the invention is the provision of means for attaching the post to a miniature electric socket, the said means also serving to attach the post to a suitable support.

With the above and other objects in view, 30 the invention further includes the following novel features and details of construction, to be hereinafter more fully described, illustrated in the accompanying drawings and pointed out in the appended claims.

35 In the drawings:—

Figure 1 is an elevation of the invention.

Figure 2 is a vertical sectional view of the same.

Figure 3 is an enlarged elevation of the 40 conductor which extends through the post and the contacts at opposite ends thereof, parts being broken away to more clearly show the structure.

Referring in detail to the drawings 45 wherein like characters of reference denote corresponding parts, the reference character 10 indicates a miniature electric lamp socket, such as the socket usually found in Christmas tree lighting outfits and in which there is provided a threaded shell 11 and a contact 12 at the bottom of the shell. A conductor wire 13 is connected to the contact 12 while a conductor wire 14 is con-

nected to the shell 11, the said conductor wires supplying current from a suitable 55 source so as to complete a circuit through a lamp within the socket 10. It is obvious of course that other types of sockets are suitable for the purpose and may be employed.

In the present invention, instead of connecting the lamp directly within the socket 10, there is provided a post 15 of suitable attractive configuration. The bottom of this post is provided with a base 16 which is adapted to rest upon the top of a support 17, while the socket 10 enters an opening 18 provided in the support, the walls of the opening and the upper end of the socket being slightly tapered as shown in Figure 2 so as to limit the entrance of the socket 70 within the opening.

Extending from the base 16 is a threaded projection 19 which engages the threads of the shell 11 and which has extending therefrom a centrally arranged contact 20. This 75 contact extends a suitable distance from an insulating plate or washer 21 which engages the lower end of the threaded extension 19 of the post 15 and which is adapted to engage the contact 12 so as to effect an electrical connection therewith. The contact 20 has secured thereto one end of a conductor wire 22 which extends upward through the post 15 and which is encased within an insulating cover 23. The opposite or upper end of the conductor 22 extends through an insulating plate 24 and has secured thereon a contact 25, the latter 80

extending within the lower end of a lamp socket 26 provided upon the upper end of 90 the post 15. The latter may thus support an electric lamp 27 whose contact 28 will engage the contact 25. Current may thus flow through the conductor 13 of the socket 10 and through the contacts 12 and 95 20, the conductor 22, the contacts 25 and 28, through the filament of the lamp 27 and back to the conductor 14 through the post 15 and the shell 11, the post 15 being covered with suitable insulating material 29, 100 for example insulating paint.

It is preferred to make the post of a soft 105 cheap metal which may be easily worked so as to reduce the cost of manufacture and in order to stiffen the base and provide a conduit for the conductor 22 there is provided

a stiffening sleeve 30. This sleeve extends substantially throughout the length of the base.

The invention is susceptible of various changes in its form, proportions and minor details of construction and the right is herein reserved to make such changes as properly fall within the scope of the appended claims.

10 Having described the invention what is claimed is:—

1. In a miniature electric lamp, the combination with a support having an opening therein, a lamp post, a base extending from the post beyond the edges of the support opening and engaging said support, a threaded projection extending from the base for engagement with the 15 socket to hold the latter in position and provide a support for the post, whereby the socket and post may be secured to the sup-

port, a lamp socket at the upper end of the post and an electric connection between the sockets.

2. A miniature lamp post comprising a standard formed of a relatively soft metal, an internally threaded lamp receiving socket at one end of the standard, an externally threaded socket engaging projection at the 20 opposite end of the standard, a reinforcing sleeve extending longitudinally within the standard, an insulating plate located at the bottom of the socket, an insulating plate at the outer end of the extension, an electric 35 conductor extending through the reinforcing sleeve and having its opposite ends extending through the insulating plates and contact members at the outer ends of the conductor and bearing against the insulating plates.

In testimony whereof I affix my signature.

JOHN L. NOLL.
